UNITED STATES PATENT OFFICE.

MOSES M. MARCUSE, OF NEW YORK, N. Y.

REVERSIBLE POURING-SPOUT FOR CANS.

1,342,639.

Specification of Letters Patent. Patented June 8, 1920.

Application filed May 22, 1916. Serial No. 99,078.

To all whom it may concern:

Be it known that I, MOSES M. MARCUSE, a citizen of the United States, residing at New York, in the county of New York and 5 State of New York, have invented a new and useful Improvement in Reversible Pouring-Spouts for Cans, of which the following is a specification.

This invention relates in general to reversible pouring spouts for cans, and more particularly to pouring spouts of the character shown in my Patent No. 1,114,011, patented Oct. 20, 1914.

The principal object of the invention is 15 the provision of a pouring spout which may be carried upon the nozzle in inverted position during marketing of the can or container provided therewith, and which may be placed in operative position by the consumer, and when so placed may be opened 20 and closed through a simple manipulation of the spout and nozzle parts.

Other objects and advantages of the invention will be apparent as it is better understood from the following description when considered in connection with the accompanying drawing illustrating a preferred embodiment thereof.

In practice, when cans or other containers 30 provided with pouring spouts for liquid contents are shipped and transported, it is highly desirable that the pouring spout be made reversible so that the same will be inclosed within the nozzle usually found upon 35 the can and thereby protected from injury, and so that also the presence of the spouts will not necessitate packaging the cans or containers in larger boxes or crates. In transporting certain classes of liquids, such 40 for instance as those used for disinfectants, it is important that the pouring spout be kept free from contact or contamination while so arranged, in order that the user will not have his hands soiled while reversing 45 the spout and placing the same in position for pouring. It is also desirable that spouts of this character may be readily opened and closed when in operative position in order that too great evaporation or 50 deterioration of the liquids may not result. Spouts constructed in accordance with my invention possess these and other advantages, as will be apparent from the following description.

55 On the drawing,

Figure 1 is a section through a pouring

spout and nozzle having the spout in operative position;

Fig. 2 is a similar view showing it reversed and in condition for shipment; 60

Fig. 3 is a perspective view of the spout member;

Fig. 4 is a top plan view of the same;

Fig. 5 is a section on the line 5—5 of 65 Fig. 4;

Fig. 6 is a perspective view of the nozzle;

Fig. 7 is a perspective view disclosed in the under side of the nozzle top or plate;

Fig. 8 is a top plan view of the same;

Fig. 9 is a perspective view of the nozzle 70 cap; and

Fig. 10 is a section on the line 10—10 of Fig. 8.

In the embodiment of my invention shown on the drawing, a round threaded nozzle 75 11 is provided at its lower end with a frangible seal 12 secured to the nozzle or can in any suitable fashion. The nozzle extends a substantial distance above the sheet 12 and is provided with an inwardly extending 80 flange 13 upon which the nozzle top and spout rest.

A nozzle top or plate 14 of diameter substantially equal to or less than the outside diameter of the nozzle is provided with an 85 aperture 15 located between one side of the center and the edge. The body of the plate is depressed to form two lips or protuberances 16 which engage in recesses 17 cut in the flange 13 of the nozzle. The spout in 90 the present instance consists of a cylindrical pouring portion 18 secured upon a base plate 19 of about the diameter of the top plate 14. The lower end 21 of the cylindrical part 18 extends through the base 95 plate 19 to which it is soldered or otherwise secured. The end 21 extends downwardly slightly beneath the under surface of the plate for a purpose which will be later described, and the cylindrical member is located so that it may be brought into registration with the aperture 15 when the spout is in operative position and pouring 100 from the container is desired.

A screw cap, generally designated at 22 105 and having an open top 23 is provided to be screwed upon the nozzle and to hold the plate and spout in position. The cap provides a flange 24 directly above the flange 13 between which two flanges the peripheral 110 edges of the plates 14 and 19 are held. The edge about the aperture 15 is made slightly

larger than the end 21 of the spout extending beneath the base plate, in the present instance, in order that the spout may accurately register with its aperture when arranged in open position. A closure sheet 25 may be provided if desired to serve as a closure for the cap when the spout is reversed and packaged ready for shipment, this sheet being discarded when it is desired

10 to bring the spout to operative position.

The spout is preferably of appropriate form to permit the upper or body part of it to be reversed and positioned through the aperture until the container reaches the consumer, this arrangement being best shown in Fig. 2 in which it will be noted that the spout is of less height than the nozzle and extends through the aperture 15 where it is out of the way. The closure sheet 25 gives 15 the can a finished appearance and can of course, if desired, bear instructions for reversing the spout to enable accurate pouring of the contents.

When the container is to be used the screw cap 22, nozzle 18 and plate 14 are removed. The seal 12 is then broken or cut away and the parts replaced in position for use. In such replacement, however, the nozzle is arranged in the upright or operative position 20 shown in Fig. 1. The plate 14, however, need not be removable, the lifting of the spout permitting a sharp instrument to be inserted through the aperture 15 to puncture the seal 12. The screw cap holds the spout 25 in any desired position, that is to say, it holds it when the spout is reversed as in Fig. 2 and also when operatively arranged as in Fig. 1. It also retains the spout in open and closed position. To open and close 30 the spout it is only necessary to loosen the cap 22 and to turn the spout about the axis of the nozzle. When in open position the lower end 21 of the spout registers with and rests in the depression 15 of the top 35 plate 14 and a depression 26 is formed in this plate in which the lower end 21 may rest when the spout has been moved about the axis of the nozzle to closed position. The cap may be screwed down after each 40 movement of the spout from open to closed and from closed to open positions to hold it against any independent movement, the flanges 24 pressing upon the base 19 holds the end 21 of the spout in the opening 15 45 or in the depression 26 depending upon whether the spout be in open or closed position. The plate is fixed against rotation so that relative movement is substantially insured between the spout and plate when the 50 former is moved to bring it to open or closed position. When the spout is open it seats firmly in the aperture 15, and when closed in the depression 26, the depth of this depression being sufficient to permit the upper 55 face of the plate 14 to contact fully with the

under face of the base 19 of the spout to seal the lower end of the spout to prevent evaporation of the contents of the container. The aperture 15 and depression 26 insure that the spout will be fully opened and fully 70 closed when moved to open or closed position.

It is thought that the invention and many of its attendant advantages will be understood from the foregoing description, and it 75 will be apparent that various changes may be made in the form, construction and arrangement of the parts without departing from the spirit and scope of the invention or sacrificing any of its material advantages, 80 the form hereinbefore described being merely a preferred embodiment thereof.

I claim:—

1. A can comprising a nozzle having a cut-out or frangible seal at its bottom, and a 85 top secured upon said nozzle and having an eccentric perforation therethrough and a depression for the seating of the lower end of the spout, an open top cap for said nozzle and a reversible eccentric spout engageable with the top of said nozzle and with the cap when in reversed and operative positions, said spout being movable into and out of registration with said perforation, substantially as specified.

2. A nozzle for cans having an imperforate frangible bottom, a top piece having an eccentric perforation and at another place an equally eccentric imperforate seat, a nozzle adapted to be inverted and to be passed 100 down through said perforation, and for pouring to be reverted with its bottom end in said perforation, and also to be adjusted with its bottom end in said seat, and means for securing said spout in any of said three 105 positions.

3. A can closure comprising, in combination, a nozzle adapted to be attached to a can body, a frangible closure attached to the lower part of the nozzle and adapted to 110 seal the opening into the can when the nozzle is so attached, a plate resting on the margin of the nozzle and having an eccentric perforation and having means engageable with the nozzle whereby it is held from rotation, a reversible spout plate resting on said 115 perforated plate and having a spout which extends down through said perforation when the spout is inverted, a closure sheet resting on the spout plate and covering the 120 opening through the spout, and a cap detachably secured to the nozzle and confining the closure sheet, the perforated plate and the spout plate when the spout is reversed, the spout plate being rotatable to close the 125 spout by an imperforate portion of the perforated plate when the spout is reverted.

4. A can closure comprising, in combination, a nozzle adapted to be attached to a can body, a frangible closure attached to the 130

lower part of the nozzle and adapted to seal the opening into the can when the nozzle is so attached, a plate resting on the margin of the nozzle and having an eccentric perforation and having means engageable with the nozzle whereby it is held from rotation, a reversible spout plate resting on said perforated plate and having a spout which extends down through said perforation when the spout is inverted, a closure sheet resting on the spout plate and covering the opening through the spout, and a flanged cap screwed to the nozzle and confining by its flange the closure sheet, the perforated plate and the spout plate when the spout is reversed, the spout plate being rotatable to close the spout by an imperforate portion of the perforated plate when the spout is reverted.

5 10 15 20 25 30 35 40 45 50 55 60 65

5. A can closure comprising, in combination, a nozzle adapted to be attached to a can body, a frangible closure attached to the lower part of the nozzle and adapted to seal the opening into the can when the nozzle is so attached, a plate resting on the margin of the nozzle and having an eccentric perforation and having means engageable with the nozzle whereby it is held from rotation, a reversible spout plate resting on said perforated plate and having a spout projecting from both sides of the plate and which extends down through said perforation when the spout is inverted, a closure sheet resting on the spout plate and covering the opening through the spout, and a flanged cap screwed to the nozzle and confining by its flange the closure sheet, the perforated plate and the spout plate when the spout is reversed, the spout plate being rotatable to close the spout by an imperforate portion of the perforated plate when the spout is reverted.

6. A can closure comprising, in combination, a nozzle adapted to be attached to a can body, a frangible closure attached to the lower part of the nozzle and adapted to seal the opening into the can when the nozzle is so attached, a plate resting on the margin of the nozzle and having an eccentric perforation and having means engageable with the nozzle whereby it is held from rotation, a reversible spout plate resting on said perforated plate and having a spout which extends down through said perforation when the spout is inverted, and a cap detachably secured to the nozzle and confining the perforated plate and the spout plate when the spout is reversed, the spout plate being rotatable to close the spout by an imperforate portion of the perforated plate when the spout is reverted.

7. A can closure comprising, in combination, a nozzle adapted to be attached to a can body, a plate resting on the margin of the nozzle and having an eccentric perforation when the spout is inverted, and a screw threaded flanged cap adjustably secured to the nozzle and confining by its flange the perforated plate and the spout plate when the spout is inverted, the spout plate being rotatable to close the spout by an imperforate portion of the perforated plate when the spout is reverted.

8. A can closure comprising, in combination, a nozzle adapted to be attached to a can body, a plate separate from and resting on the margin of the nozzle and having an eccentric perforation, a reversible spout plate resting on said perforated plate and having a spout which extends down through such perforation when the spout is inverted, and a cap adjustably secured to the nozzle and confining the perforated plate and the spout plate when the spout is inverted, the spout plate being rotatable to close the spout by an imperforate portion of the perforated plate when the spout is reverted.

9. A can closure comprising, in combination, a nozzle adapted to be attached to a can body, a plate resting on the margin of the nozzle and having an eccentric perforation, a reversible spout plate resting on said perforated plate and having a spout which extends down through such perforation when the spout is inverted, and a cap adjustably secured to the nozzle and confining the perforated plate and the spout plate when the spout is inverted, the spout plate being rotatable to close the spout by an imperforate portion of the perforated plate when the spout is reverted.

10. A can closure comprising, in combination, a nozzle adapted to be attached to a can body, a plate resting on the margin of the nozzle and having an eccentric perforation, a reversible spout plate resting on said perforated plate and having a spout which extends down through such perforation when the spout is inverted, and a screw threaded flanged cap adjustably secured to the nozzle and confining by its flange the perforated plate and the spout plate when the spout is inverted, the spout plate being rotatable to close the spout by an imperforate portion of the perforated plate when the spout is reverted.

11. A can closure comprising, in combination, a nozzle adapted to be attached to a can body, a plate separate from and resting on the margin of the nozzle and having an eccentric perforation, a reversible spout plate resting on said perforated plate and having a spout which extends down through such perforation when the spout is inverted, and a screw threaded flanged cap adjustably secured to the nozzle and confining by its flange the perforated plate and the spout plate when the spout is inverted, the spout plate being rotatable to close the spout by an imperforate portion of the perforated plate when the spout is reverted.

12. A can closure comprising, in combination, a nozzle adapted to be attached to a can body, a plate resting on the margin of the nozzle and having an eccentric perforation, a reversible spout plate resting on said perforated plate and having a spout which extends down through such perforation when the spout is inverted, and a screw threaded flanged cap adjustably secured to the nozzle and confining by its flange the perforated plate and the spout plate when the spout is inverted, the spout plate being rotatable to close the spout by an imperforate portion of the perforated plate when the spout is reverted.

plate when the spout is inverted, the spout plate being rotatable to close the spout by an imperforate portion of the perforated plate when the spout is reverted.

- 5 12. In a can closure, the combination of a plate formed with a perforation and an imperforate seat, a rotatable spout plate having a spout the pouring end of which is adapted to pass through said perforation
10 when the spout is inverted and the receiv-

ing end of which is adapted to register with said perforation or to engage in said seat when the spout is reverted, and means for confining said plates.
